(57) **CLAIM**

The ornamental design for a camera-printer combination, as shown and described.

DESCRIPTION

FIG. 1 is a front perspective view of the camera-printer combination, showing the relationship of the printer portion of the combination to a digital camera to be docked therewith;

FIG. 2 is a rear perspective view of the printer of FIG. 1; FIG. 3 is a top view of the printer; and, FIG. 4 is a left side view of the printer.

The broken lines shown in FIGS. 1-4 are for illustrative purposes only, and form no part of the claimed design.
